(57) **CLAIM**

The ornamental design for a glass rinser, as shown and described.

DESCRIPTION

FIG. 1 is a front, right, and top perspective view of a glass rinser, showing my new design;

FIG. 2 is a rear, left, and bottom perspective view of the glass rinser in FIG. 1;

FIG. 3 is a front, right, and bottom perspective view of the glass rinser in FIG. 1;

FIG. 4 is a front elevation view thereof;

FIG. 5 is a rear view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines shown in the drawings are included for the purpose of illustrating portions of the glass rinser that form no part of the claimed design.

1 Claim, 9 Drawing Sheets
